DESIGN FOR A FOUNTAIN PEN

Leslie F. Wooldridge, Vancouver, British
Columbia, Canada

Application August 30, 1934, Serial No. 53,121

Term of patent 7 years

To all whom it may concern:

Be it known that I, Leslie F. Wooldridge, a subject of the King of Great Britain, residing at Vancouver, in the Province of British Columbia and Dominion of Canada, have invented a new, original, and ornamental Design for a Fountain Pen, of which the following is a specification, reference being had to accompanying drawing, forming part thereof.

Fig. 1 is a perspective view of the fountain pen in an open position, showing my new design.

Fig. 2 is a side elevation of same at a different angle from that shown in Fig. 1 looking in the direction of the arrow in Fig. 3;

Fig. 3 is an end view of the fountain pen looking toward the right of Fig. 2; and

Figure 4 is a side elevation of the pen similar to Fig. 2, but with the cap covering the pen point.

I claim:

The ornamental design for a fountain pen, as shown and described.

LESLIE F. WOOLDRIDGE.
